CLAIM

(52) **U.S. Cl.**

The ornamental design for a microscope stage-top incubator system, as shown and described.

USPC **D24/163**

DESCRIPTION

(58) **Field of Classification Search**

USPC D24/163, 216, 223–225, 231, 232;
D10/81; D16/130, 131; 422/500, 547,
422/62–65, 67; 435/287.1, 287.3, 303.1;
436/43, 45, 47; 359/391, 395

CPC G02B 21/26; G02B 21/30; G02B 21/34;

FIG. 1 is a first front, top perspective view of an embodiment

U.S. PATENT DOCUMENTS

of a microscope stage-top incubator system of our new design;

2,440,472 A 4/1948 Horner
D297,564 S 9/1988 Yamamoto et al.
D333,187 S 2/1993 Omi
D342,792 S 12/1993 Charm et al.

FIG. 2 is a right side view thereof;

FIG. 3 is a left side view thereof;

FIG. 4 is a rear view thereof;

FIG. 5 is a front view thereof;

FIG. 6 is a top view thereof;

FIG. 7 is a bottom view thereof; and,

FIG. 8 is a second front, top perspective view thereof.

The broken lines illustrate portions of the microscope stage-top incubator system that form no part of the claimed design.
